United States Patent Office

Des. 183,490
Patented Sept. 9, 1958

183,490

WASTE RECEPTACLE

William Taylor Jones, Scranton, Pa.

Application July 10, 1957, Serial No. 46,887

Term of patent 14 years

(Cl. D44—6)

FIG.2.

FIG.1.

FIG. 3.

FIG. 4.

I claim:

The ornamental design for a waste receptacle, as shown.
